(57) **CLAIM**

The ornamental design for a cleaning device attachment, as shown and described.

DESCRIPTION

FIG. 1 is a front perspective view of a cleaning device attachment showing my new design;

FIG. 2 is a front plan view of the cleaning device attachment of FIG. 1;

FIG. 3 is a rear plan view of the cleaning device attachment of FIG. 1;

FIG. 4 is a left side view of the cleaning device attachment of FIG. 1;

FIG. 5 is a right side view of the cleaning device attachment of FIG. 1;

FIG. 6 is a top plan view of the cleaning device attachment of FIG. 1; and,

FIG. 7 is a bottom plan view of the cleaning device attachment of FIG. 1.

The features shown in broken lines in FIGS. 6 and 7 are for the purpose of illustrating portions of the cleaning device attachment that form no part of the claimed design. The dash-dot lines shown in FIGS. 3 and 6 define the bounds of the claimed design and form no part thereof.
